(57) **CLAIM**

The ornamental design for a container rim with rounded corners, as shown and described.

DESCRIPTION

FIG. 1 is a perspective view of a container rim with rounded corners showing our new design;

FIG. 2 is a top plan view thereof; and,

FIG. 3 is a side elevation view thereof.

The features shown in broken lines depict environmental subject matter only and form no part of the claimed design.

1 Claim, 2 Drawing Sheets

FIG. 1

FIG. 2.

FIG. 3.
